UNITED STATES PATENT OFFICE

JOHN O. GOODWIN, OF AKRON, OHIO, ASSIGNOR TO SEIBERLING RUBBER COMPANY, OF BARBERTON, OHIO, A CORPORATION OF DELAWARE

HEEL MOLDING METHOD

Application filed October 7, 1929. Serial No. 397,900.

This invention relates to the manufacture of rubber heels of the type employing a semi-stiff, perforable, nonmetallic nailing insert or layer in the attaching face.

Such heels have many advantages over those employing embedded metal washers or other rigid nail-retaining means, but their manufacture is attended with difficulties largely due to the tendency of the mailing insert to become displaced in the heel body during molding, and during the charging of the molds with body rubber when performed by a mold-filling machine.

The object of my invention is to overcome, in an improved manner, the difficulties encountered in making heels of the type referred to. This application covers the method disclosed in my prior application Ser. No. 356,003, filed April 18, 1929, together with additional matter, and is a continuation in part of said application.

Of the accompanying drawing:

Fig. 1 is a plan view showing the attaching face of one form of heel produced by the present invention.

Fig. 2 is a longitudinal section of the heel on the line 2—2 of Fig. 1.

Fig. 3 is a cross section on the line 3—3 of Fig. 1.

Fig. 4 is a partial longitudinal section showing the heel mold in the course of being charged with body rubber in a mold-filling machine.

Fig. 5 is a partial longitudinal section showing the mold closed upon the heel.

Contrary to the usual practice with the washer-insert and some other types of heels, the heel in this case is molded and vulcanized with its attaching face down in the mold cavity, and the floor of said cavity is shaped to form said attaching face, the latter preferably being more or less concave. In following this practice heretofore, it has recently been proposed to anchor the nailing insert against displacement in the plane of the heel, by locating an upwardly-projecting boss on the floor of the mold cavity, to engage the inner edges of an annular face-insert, the finished heel having a central recess conforming to said boss. While this expedient re-

sults in securing the insert as a whole against displacement, it still permits some flowing of the outer edges thereof during vulcanization, and that portion of the insert adjacent the breast edge may become more or less displaced when the rubber pressure is exerted toward that edge by running the mold cavities through a filling machine rear end foremost, which has been found to be the best practice. Furthermore, when the insert is placed on the boss as heretofore arranged, a tendency of said insert to rise or curl up at the outer edges has been observed.

My present invention includes certain steps and devices for externally anchoring the insert, especially at the breast edge, and for counteracting its tendency to curl up or assume a non-flat condition, which steps and devices may, if desired, supplement and coact with the former expedient referred to.

Referring to the drawing, 10 is a vulcanized, soft-rubber heel body, and 11 is a nail-head retaining layer or insert embedded in and forming part of the attaching face of the heel. Said attaching face is preferably slightly dished or concave and provided around its side and rear edges with a beveled or upwardly inclined edge lip 12 on the cushion body 10 to form a tight edge closure against the shoe bottom. The layer 11 may be of any suitable composition, preferably including soft rubber to render said layer flexible and more or less resilient, and enable it to be integrally vulcanized to the rubber cushion body 10. The rubber of this layer may be stiffened with an intermixture of a suitable organic, fibrous material such, for example, as animal hair.

Located outside of the nailing zone which surrounds the central portion of the attaching face, along the outer edges of the attaching layer 11, are a series of recesses 13, 13^a, 14, 14^a, elongated in the plane of the heel and parallel respectively to the outer side and rear edges 15, 15^a and the forward or breast edge 16 of the heel, the two forward corner recesses 14^a being L-shaped. Of these recesses, the ones 14, 14^a adjacent the breast edges are the more important and the others may in some cases be omitted. The number,

relative length and disposition of the recesses may be varied, but it is important to have the one or ones at the breast edge of the insert long enough to prevent such outward flow or displacement of said insert as would result in a defective heel.

The side and rear recesses are separated by bridges or solid portions 17 of the heel material, flush with the upper face of layer 10 11 and integrally uniting the edges of said layer with the side marginal portions of the rubber body 10. The breast recesses 14, 14^a are separated by similar bridges 18. The several recesses collectively occupy the major portion of the corresponding edges of the attaching layer along which they extend, this feature being more important at the breast edge for the reason stated.

I have further shown a D-shaped recess 19 in the central region of the attaching layer 11, with its edges parallel to the outline of the heel, and surrounded by the nailing zone, said recess preferably extending clear through or perforating the layer 11, and being formed in the blank for said layer, which is cut in annular, heel-shaped form before placing in the mold. In the center of the recess 19 is a supporting stud or column 20 forming part of the rubber cushion body 10, for a purpose hereinafter described.

The several recesses in the attaching face of the heel are formed by, or mate with, complementary projections formed on the mold. 21 is the body plate of the mold, formed with molding cavities 22, and 23 is the top or cover plate, the under side of the latter being shaped over the mold cavities to form the tread faces of the heels, which may be approximately flat as shown and provided with the usual raised, non-slip, and/or brand markings.

The bottom wall or floor of each mold cavity is shaped to form the attaching face of the heel including the flexible marginal lip 12, and is shown as provided with a central, upwardly-projecting, annular boss 24 corresponding to the large central recess 19 in the heel, and with upwardly-projecting ribs 25, 26 of less height than the boss, for forming the rear recess 13^a and the breast recess 14, respectively, in the heel, other similar ribs being provided for forming the other marginal recesses.

The height of the boss 24 is made greater than the thickness of the nailing insert 11, so that when said insert is placed on said boss and supported on the floor of the mold cavity it will tend to lie flat and not curl up or rise at its outer edges, the frictional hold of the ribs such as 25, 26 on these outer edges further tending to hold the insert flat. Since a boss of this height rather deeply indents the heel body, I prefer to centrally recess the boss 24 to form the rubber stud or column 20 for supporting the central tread wall of the heel,

although modified expedients could be adopted and this supporting member might be omitted.

In the molding of the heel under vulcanizing heat and pressure, the mold ribs such as 25 and 26 externally anchor the nailing insert 11 and prevent it from displacement or flowing to the edges of the body rubber and producing defective heels. These ribs, or one or more of them for forming one or more of the recesses 13, 13^a, 14, 14^a in the seating face of the heel, and especially the rib or ribs at the breast edge, could be employed as the sole expedient for anchoring the insert 11 against displacement and flowing, and the boss 24 with its corresponding heel recess 19 could be omitted. However, I prefer, especially with the softer stocks, to provide one or more central mold bosses such as 24, either solid, or annular as shown, or of other form, for also internally anchoring the insert, in which case the boss and ribs supplement each other and mutually relieve each other of a part of the anchoring duty. It will also be understood that the function of the deep boss 24 in causing the insert to lie flat could be employed apart from the external anchoring ribs.

The marginal mold ribs, or either of them, and said ribs or either of them in conjunction with the mold boss 24, together with the operations performed thereby, are useful not only in preventing flow and displacement of the nailing insert due to molding pressure and heat, but also in avoiding displacement due to pressure of the body stock during filling of the mold in a machine. Fig. 4 represents a portion of such a machine including an upper or nozzle plate 27 and a lower bed plate 28, between which the mold plate 21 is forced rightward, in the direction of the arrow, by a suitable pusher. 29 is a funnel-shaped nozzle chamber and 30 is plastic rubber composition adapted to be forced therethrough by suitable means and extruded through the narrow outlet slot of the nozzle into the mold cavities 22, said slot extending transversely for the full width of the mold. Thereby the nailing insert 11 is progressively embedded in the plastic body-rubber composition, beginning at the rear end of the heel and ending at the breast end, since the mold plate is pushed through with its cavities rear-end foremost so that the pressure of the rubber will be mostly in the direction of the breast edge and any occasional imperfections caused by displacement or overflow of the insert will occur at the breast edge where they will be least conspicuous when the heel is applied to a shoe. Obviously the rib or ribs such as 26 which are located adjacent the breast edge are most effective in preventing such displacement in the filling operation as thus carried out.

After the mold has been filled, its cover plate 23 is applied, the mold is placed in a heater press and the heels vulcanized in the

usual manner, the vulcanization resulting in an integral union between the heel components.

While a preferred embodiment has been described, there is opportunity for considerable variation in the method and apparatus as here disclosed, without departing from my invention as defined in the claims, and I do not wish to be limited except as thus defined.

10 I claim:

1. The method of making rubber heels which comprises inserting a plastic attaching layer in the top side of a cushion rubber heel body, confining said layer within the margin of the heel, along an outer edge of said layer, during its insertion in the body rubber, sufficiently to prevent flow thereof to the adjacent outer edge face of the heel, and vulcanizing the heel under heat and molding pressure.

2. The method of making rubber heels which comprises inserting a plastic attaching layer in the top side of a cushion rubber heel body, externally confining said layer within the margin of the heel along the breast edge of said layer for the greater part of its length during the insertion of said layer in the body rubber to prevent flow of said layer to the adjacent breast edge of the heel, and vulcanizing the heel under heat and molding pressure.

3. The method of making rubber heels which comprises inserting a plastic attaching layer in the top side of a cushion rubber heel body, externally confining said layer within the margins of the heel along the side edges and breast edge of said layer for the greater part of the length of said edges during the insertion of said layer in the body rubber to prevent flow of said layer to the adjacent edge faces of the heel, and vulcanizing the heel under heat and molding pressure.

4. The method of making rubber heels which comprises inserting a plastic attaching layer in the top side of a cushion rubber heel body, confining said layer both internally and externally within the margins of the heel, during the insertion of said layer in the body rubber, and vulcanizing the heel under heat and molding pressure.

5. The method of making rubber heels which comprises inserting, in the top side of a cushion rubber heel body, a perforated plastic blank for attaching layer, confining said layer by the edges of its perforation and also by an outer edge, within the margin of the heel, during the insertion of said layer in the body rubber, and vulcanizing the heel under heat and molding pressure.

6. The method of making rubber heels which comprises inserting, in the top side of a cushion rubber heel body, a centrally recessed blank for an attaching layer, confining said layer by the edges of its central recess, and also along its breast edge for the greater part of the length of said edge, dur-

ing the insertion of said layer in the body rubber, and vulcanizing the heel under heat and molding pressure.

7. The method of making rubber heels which comprises anchoring a nailing insert by an outer edge thereof at the bottom of a mold cavity, progressively embedding said insert by extruding plastic rubber composition into said mold cavity while the insert is so anchored, and vulcanizing the heel in [75] said cavity.

8. The method of making rubber heels which comprises externally anchoring a nailing insert by its breast edge in a mold cavity, and progressively extruding plastic rubber into said cavity, from the rear to the breast end, while the insert is so anchored to embed said insert.

9. The method of making rubber heels which comprises anchoring a perforated nail- 85 ing insert by its internal and external edges in a mold cavity, and progressively extruding plastic rubber composition into said cavity to embed the insert, while the latter is so anchored. 90

10. The method of making rubber heels which comprises anchoring a perforated, flexible, non-metallic nailing member at the bottom of a mold cavity by means of a projection deeper than the thickness of the member, and applying body rubber to said member while the insert is so anchored. 95

11. The method of making rubber heels which comprises internally anchoring a perforated, flexible, non-metallic nailing insert 100 at the bottom of a molding cavity by means of a projection deeper than the thickness of the insert and progressively embedding said insert by extruding plastic rubber composition into said cavity while the insert is so anchored. 105

In witness whereof I have hereunto set my hand this 2nd day of October, 1929.

JOHN O. GOODWIN.
